UNITED STATES PATENT OFFICE.

PHILIP RICE, OF BERKELEY, CALIFORNIA.

VIBRATORY APPARATUS.

1,164,018.

Specification of Letters Patent. Patented Dec. 14, 1915.

Application filed December 6, 1912. Serial No. 735,301.

To all whom it may concern:

Be it known that I, PHILIP RICE, a citizen of the United States, residing at Berkeley in the county of Alameda and State of California, have invented certain new and useful improvements in Vibratory Apparatus, of which the following is a specification.

The object of my invention is to provide an improved vibratory apparatus principally designed for use in the treatment of the ear and adapted to effect rapid pulsations against an air body for the purpose of generating intermittent discharges of air.

One of the objects of my invention is to provide a pulsating mechanism, one member of which is operated partly by electrical means and partly by gravity and mechanical means.

A further object of the invention is to provide mechanism which will generate intermittent discharges of air at a high rate of speed and which will at all times be accurately and sensitively responsive to control of the operator.

Other objects and novel features of my invention will be more fully disclosed in the accompanying drawings, and will be more particularly pointed out in and by the appended claims.

In the drawings: Figure 1 is a view in side elevation of a device embodying one form of my invention. Fig. 2 is a plan view thereof. Fig. 3 is a vertical sectional view of Fig. 1 taken on line 3-3 of Fig. 2. Fig. 4 is a plan view of a portion of the device of Fig. 3 shown detached therefrom. Fig. 5 is a vertical sectional view on a solenoid core plunger. Fig. 6 is a sectional view on line 6-6 of Fig. 4. Fig. 7 is a diagrammatical view showing the electrical circuit for my device.

Like characters of reference designate similar parts throughout the different figures of the drawings.

In the specific form shown a base 1 is provided having a hollow interior 2 and a shoulder 3 on which a diaphragm 4 is disposed. A casing 5 is disposed upon a yielding washer 6 which is interposed between the diaphragm 4 and the casing 5 and the parts are secured as illustrated by screws 7. The diaphragm 4, together with base 1, forms an air chamber, as indicated at 2, which is provided with an intake 8. An outlet for the chamber 2 is provided with a valve 9 and

a flexible tube 10 having any suitable or desired form of instrument 11 at the discharge end thereof. The casing 5 is preferably hollowed out and is provided with a supporting plate or disk 12 on which a solenoid 13 is disposed. The solenoid is provided with an interior sleeve 14, forming a core bore, and providing a wearing guiding part for a plunger 15 which is also the core of the solenoid.

The plunger 15, as illustrated in Fig. 5, is provided with a lower chamber 16 in which is disposed a spring 17 mounted upon a removable tapped plug 18, for removal and insertion of the spring 17. A cap or top 19 is mounted on spring 17 and lies in the path of and is adapted to be engaged by a plunger rod 20. The plunger 15 is provided with a contracted portion having a bore 21 to guide the lower end of the plunger rod 20. The contracted portion provides a shoulder 22 upon which the lower end of a spring 23 rests, the upper end of the spring engaging the collar 24 secured to the rod 20. The upper end of the rod 20 is guided in a sleeve 25 which is tapped into the plunger 15, as shown in Fig. 5. The extremity of the rod 20 is provided with a removable impact tip member 26 formed of non-conducting material and which is removably secured to the rod 20, as illustrated.

It will be seen from the foregoing that relative movement of the rod 20 with respect to the plunger 15 which is sufficient to cause the rod 20 to engage the part 19, will be resisted first by a spring 23 and subsequently by a spring 17, thereby affording a plurality of spring devices offering a cumulatively increasing resistance to relative movement of the rod 20 with respect to the plunger 15. The plunger 15 is disposed in the solenoid, as indicated in Fig. 3, and when the solenoid is energized the plunger will be lifted, as a solenoid core, and when the solenoid is deenergized the plunger will drop by gravity into engagement with the diaphragm 4 so that the resulting concussion in chamber 2 will generate intermittent discharges of air through instrument 11. A suitable stop is provided limiting upward movement of the core 15 under the action of solenoid 13 and such upward movement of plunger 15 will be arrested by the spring devices 23 and 17 so that the recoil of the spring devices will act, in addition to what-

ever gravity action can take place, to rapidly move the plunger into engagement with diaphragm 4. It will thus be seen that the part 15 acts as the core of a solenoid during its upward movement, or during a movement in one direction, and that in a reverse movement it acts as a mechanical plunger, the reverse movement being the positive movement, which is downward and the initial movement which is upward, being the negative movement, in the form shown.

The stop device which serves to limit upward movement of the plunger under the action of the solenoid is herein shown as a short circuiting means, or means for cutting out the solenoid to deenergize the same, and the same may consist of spring contact arms 27 and 28 having opposing contact tips 29 and 30, which may be of platinum, or other suitable metal. An abutment 31 positively limits upward movement of arm 28 against the action of the plunger rod upon arm 27. The abutment 31 is desirably adjustable and may be in the form of a screw tapped into the cap 32 of the casing 5. A lock nut 33 serves to hold the abutment in its adjusted position.

Arm 28 is connected with one link 34 from a source of supply of current 35. Arm 28 is also connected by conductor 36 with one terminal of the solenoid winding. The other lead 37 from the source of current 35 is electrically connected with a plug 38 which is mounted in an insulating bushing 39 in the casing 5. An actuating key 40, provided with a contact head 41, is slidably mounted in the plug 38 and is held in the position shown with the head 41 against the plug 38 by a spring 42, the latter being interposed between the bushing 39 and the end 43 of the key. The head 41 is adapted to close circuit, when the key is pressed inwardly, by engaging a spring contact 44 mounted upon a contact strip 45. Contact strip 45 is connected with arm 27 by a conductor 46 and the strip 45 is also connected by a conductor 47 with one terminal of the solenoid winding.

It will be seen by reference to Fig. 4 that current flows from lead 34 through arm 28 and the solenoid out to strip 45 and contact spring 44 through which and the head 41 circuit is completed through lead 37 back to the source of current. It will thus be seen that when the key is pressed inwardly to engage the head 41 with the spring 44 circuit will be closed and the solenoid will be energized to elevate the plunger 15 and cause an impact of the tip 26 with arm 27 thereby engaging the contact 29 with contact 30 of arm 28. This will short circuit the current and cut out the solenoid and the resulting spring action of the spring devices 23 and 17 will drive the plunger 15 downwardly against the diaphragm 4. Short circuiting is ef-

fected through arm 28 to arm 27 through conductor 46, strip 45 to spring 44 and through the key and plug 38 to conductor 37. It will thus be seen that the key is held in an operating position to close circuit and that the operation of the core of the solenoid will intermittently energize and deenergize the solenoid so as to cause an electrical negative and a mechanical positive movement of the plunger 15 in a very rapid and efficient manner.

While I have herein shown and described one specific form of my invention I do not wish to be limited thereto except for such limitations as the claims may import.

I claim:—

1. An apparatus of the class described comprising a freely moving resilient plunger.

2. A vibratory apparatus comprising in combination, a vertically disposed solenoid winding, a resilient plunger core for said winding, a stop against which said core impinges when actuated by said winding, and a blow receiving element at the opposite end of the path of said core from said stop.

3. A vibratory apparatus comprising in combination, a vertically disposed solenoid winding, a resilient plunger core for said winding, a stop against which said core impinges when actuated by said winding, and a blow receiving element at the opposite end of the path of said core from said stop, said blow receiving element comprising a diaphragm.

4. A vibratory apparatus comprising in combination, a vertically disposed solenoid winding, a resilient plunger core for said winding, a stop against which said core impinges when actuated by said winding, a blow receiving element at the opposite end of the path of said core from said stop, said blow receiving element comprising a diaphragm, and means forming an air chamber beneath said diaphragm.

5. A vibratory apparatus comprising in combination, a vertically disposed solenoid winding, a resilient plunger core for said winding, a stop for said core when the same is actuated by said winding, said stop including means for deenergizing said winding, and a blow receiving element at the opposite end of the path of said core from said stop.

6. A vibratory apparatus comprising in combination, a vertically disposed solenoid winding, a resilient plunger core for said winding, a stop for said core when the same is actuated by said winding, said stop including means for deenergizing said winding, and a blow receiving element at the opposite end of the path of said core from said stop, said blow receiving element comprising a diaphragm, and means forming an air chamber beneath said diaphragm.

7. In a reciprocating electric motor, a freely moving resilient plunger.
8. A vibratory apparatus comprising in combination, a vertically disposed solenoid winding, a freely moving resilient plunger core for said winding, a stop for said core at the end of its movement when said winding is energized, said stop including means for deenergizing said winding, and a blow receiving member at the opposite end of the movement of said core from said stop.
9. A vibratory apparatus comprising in combination, a hollow casing, a solenoid winding mounted vertically within said casing, a core plunger for said solenoid, a circuit controlling device disposed in the path of said plunger near the upper end of said winding, said device being adapted to deenergize said winding when struck by said

solenoid, said plunger comprising a stem 20 and a body portion, said stem being slidably mounted within the body portion axially thereof and projecting beyond the upper end thereof, said body portion being provided with a head and a contracted portion 25 spaced apart and with which said stem has a sliding engagement, said stem being provided with a collar normally in contact with said end of the body, and a spring coiled around said stem and interposed between 30 said collar and said contracted portion.

In testimony whereof I affix my signature in presence of two witnesses.

PHILIP RICE.
